UNITED STATES PATENT OFFICE

ROBERT N. SMITH, OF KANSAS CITY, MISSOURI, ASSIGNOR OF ONE-HALF TO JAMES L. HOGIN, OF KANSAS CITY, KANSAS.

CAR DOOR LOCK

Application filed November 4, 1929, Serial No. 404,636. Renewed June 6, 1931.

My invention relates to improvements in car door locks. It relates particularly to locks of automobiles in which the doors close against jamb seats.

One of the objects of my invention is to provide a door lock of the kind described with novel means for forcing the door of an automobile toward the open position, when the door handle at the inside of the door is operated to retract the bolt, thus making a close fitting door easy to open from the inside of the car.

A further object of my invention is to provide novel means of the kind described, which is simple, cheap, strong, durable, not likely to get out of order, and which can readily be adapted to car door locks of the types in common use.

The novel features of my invention are hereinafter fully described and claimed.

In the accompanying drawings, which illustrate the preferred embodiment of my invention,

Fig. 1 is a side elevation of a lock provided with my improvement.

Fig. 2 is a section on the line 2—2 of Fig. 1, showing the door fully closed, the bolt engaged with the jamb, and the push screw retracted to the inactive position.

Fig. 3 is an enlarged bottom view of the lock, portions thereof being omitted.

Fig. 4 is a view similar to Fig. 2, the door bolt being retracted, the push screw projected, and the door partly opened.

Fig. 5 is an enlarged section on the line 5—5 of Fig. 2.

Fig. 6 is a section on the line 6—6 of Fig. 5. Similar characters of reference designate similar parts in the different views.

1 designates a lock casing of usual type shown mounted on a car door 2 and having the usual bolt 3 retractile by an oscillative handle 4, of usual type, at the inner side of the door.

45 The door 2 cooperates with a seat 5 of a usual type of door jamb 6.

Forcing the door toward the open position, when the handle 4 is operated to retract the bolt 3 from the jamb 6, is a push member, 50 comprising, preferably, a horizontal screw

7, which has threaded engagement with a vertical inner plate 8 with which the casing 1 is provided, Figs. 1, 3 and 6. The outer wall of the casing 1 has a smooth hole through which the screw 7 extends. The plate 8 has through it a transverse hole provided with a circular row of recesses 9 in which the threads 10 of the push screw are slidably fitted.

When the screw 7 is turned in a counter clockwise direction, as viewed in Figs. 1, 2, 5 and 6, it will move through the plate 8 so as to project from the casing 1, as shown in Fig. 4, and in so moving it will push against the seat 5 of the jamb 6, thus, the bolt 3 being retracted, forcing the door 2 toward the open position, and making it easy for the operator within the car to fully open the door.

For so turning the push screw when the handle 4 is swung to retract the bolt 3, said screw 7 has a crank arm 11 to which is pivoted one end of a link 12, the other end of which is pivoted to a crank 13 mounted on and oscillative with the handle 4.

Sufficient lost motion is provided to permit the bolt 3 to be fully withdrawn before the screw 7 engages the seat 5 to force the door open.

In the operation, the operator in the car swings the handle 4 to retract the bolt 3 from the jamb 6, and in such movement of the handle, the crank 13, link 12, and crank arm 11 turn the screw 7 to the position shown in Fig. 4.

The door will thus be partly opened by the screw 7 pushing against the jamb seat 5.

When the door is closed and the handle is returned to its original position, shown in Fig. 1, the crank 13, link 12 and crank arm 11 will retract the screw 7 inwardly to the position shown in Figs. 2, 3 and 6.

A small opening movement of the door by the push screw 7 is sufficient to permit the operator to easily open the door the rest of the way.

I do not limit my invention to the structure shown and described, as modifications, within the scope of the appended claims, may be made without departing from the spirit of my invention.

What I claim is:—

1. In a car door lock, the combination with a door lock having a lock casing, a handle, and a bolt retractible by said handle, of a push member oscillative in and having threaded engagement with said casing such that when turned in one direction it will project from said casing and adapted to push against a door jamb so as to open a closed door adapted to carry said lock and cooperating with said jamb, and means actuated by said handle, when the latter is operated to retract said bolt, for turning said member in said direction to the pushing position.
2. In a car door lock, the combination with a door lock having a lock casing, a handle, and a bolt retractible by said handle, of a push member oscillative in and having threaded engagement with said casing such that when turned in one direction it will project from said casing and adapted to push against a door jamb so as to open a closed door, adapted to carry said lock, said push member having a crank arm, a crank on said handle, and a link connecting said crank and said crank arm, for turning said push member in said direction to the pushing position, when said handle is operated to retract said bolt.
3. In a car door lock, the combination with a door jamb having a seat, a door cooperating with said seat and having a lock having a casing, a handle, and a bolt retractible by said handle, of a push member oscillative in and having threaded engagement with said casing such that when turned in one direction it will project from said casing and adapted to push against said seat so as to open said door, and means actuated by said handle, when the latter is operated to retract said bolt, for turning said member in said direction.
4. In a car door lock, the combination with a door jamb having a seat, a door cooperating with said seat and having a lock provided with a casing, a handle, and a bolt retractible by said handle, of a screw having oscillative threaded engagement with said casing, and when turned in one direction projecting from said casing, and adapted, when so turned, to push against said seat so as to open said door, and having a crank arm, a crank on said handle, and a link connecting said crank and said crank arm, for turning said screw in said direction when said handle retracts said bolt.

In testimony whereof I have signed my name to this specification.

ROBERT N. SMITH.
